(57) **CLAIM**

We claim the ornamental design for a handle for a buggy, as shown and described.

DESCRIPTION

FIG. 1 is a perspective view of the new design of a handle for use in buggy;

FIG. 2 is a front view of the new design of the handle;

FIG. 3 is a left side elevation view of the handle;

FIG. 4 is a rear view of the handle;

FIG. 5 is a right view of the handle;

FIG. 6 is a top view of the handle;

FIG. 7 is a bottom view of the handle; and,

FIG. 8 is a second perspective view of the handle.

The broken lines shown in the figures are for illustrative purposes only and form no part of the claimed design.
